UNITED STATES PATENT OFFICE

115,595

DESIGN FOR A COAT

Gladys E. Felger, Santa Barbara, Calif.

Application October 4, 1938, Serial No. 80,234

Term of patent 3½ years

To whom it may concern:

Be it known that I, Gladys E. Felger, a citizen of the United States, residing at Santa Barbara, in the county of Santa Barbara and State of California, have invented a new, original, and ornamental Design for Coats, of which the following is a specification, reference being had to the accompanying drawing, forming a part thereof, and in which:

Fig. 1 is a front view of a coat showing my new design.

Fig. 2 is a rear view of the coat shown in Fig. 1.

Fig. 3 is an enlarged fragmentary view of the design appearing around the body of the coat shown in Figs. 1 and 2.

Fig. 4 is an enlarged fragmentary view of the design encircling the sleeve of the coat shown in Figs. 1 and 2.

Fig. 5 is an enlarged fragmentary view of the design appearing around the collar of the coat shown in Figs. 1 and 2.

I claim:

The ornamental design for a coat, as shown.

GLADYS E. FELGER.
